UNITED STATES PATENT OFFICE.

OTIS A. MYGATT, OF NEW YORK, N. Y.

DESIGN FOR A LAMP SHADE OR GLOBE.

SPECIFICATION forming part of Design No. 30,266, dated February 28, 1899.

Application filed January 16, 1899. Serial No. 702,366. Term of patent 14 years.

To all whom it may concern:

Be it known that I, OTIS A. MYGATT, a citizen of the United States, residing at New York, in the county of New York and State 5 of New York, have invented a certain new and useful Design for a Lamp Shade or Globe, of which the following is a specification, reference being had therein to the accompanying drawings.

10 This invention relates to a new, useful, and original shape or configuration of an article of manufacture known as a "lamp shade or globe" and a new and original ornament or impression to be placed on or molded in said 15 lamp shade or globe.

Figure 1 is a side elevation of a lamp shade or globe (so called in the trade) illustrating the design so far as may be done by a line drawing. Fig. 2 is a horizontal section of 20 the wall of the shade on line 2 2 of Fig. 1. Fig. 3 is a broken vertical section of the wall of the shade on line 3 3, Fig. 1.

The shade is composed of glass or crystal of transparent character. The general con- 25 tour of the shade is spherical, as shown in the drawings. The outer surface of the shade has horizontal ribs or prisms projecting from the general surface of the glass, and the inner surface of the shade has vertical ribs, all 30 these ribs being integral with the glass and all being produced (as the shades are now constructed) by molding when the glass is in plastic condition. The ribs on the inner surface of the glass are visible through the 35 transparent medium, and without close examination might be supposed to be on the outer surface of the glass.

The effect of the vertical and horizontal ribs or prisms, the horizontal ribs projecting outwardly and the vertical ribs projecting inwardly from the general thickness of the glass, gives to the glass the appearance of being made up of small individual crystals or beads arranged in regular horizontal and vertical rows.

45 A shade made of transparent glass properly ribbed in the manner described has the property of rendering objects within it practically invisible, while transmitting in a diffused form substantially all the light falling upon 50 it—that is, the shade appears translucent, although the glass is transparent, the refraction of the light-rays by the inclined surfaces preventing a direct transmission of such rays and giving an opalescent or iridescent 55 appearance to the shade when seen from different angles and under different lights.

Such a globe when applied in proper manner to an artificial light of any kind is not only pleasing to the eye, but has the effect of 60 softening the light, thereby rendering the light more pleasing also.

What I claim is—

The design for a lamp shade or globe, as 65 herein described and shown.

In testimony whereof I affix my signature in presence of two witnesses.

OTIS A. MYGATT.
